SHEET METAL FRAME FOR GRILLES AND THE LIKE

Walter W. Kennedy, Rockford, Ill., assignor to
Barber-Colman Company, Rockford, Ill., a cor-
poration of Illinois

Application February 8, 1949, Serial No. 748

Term of patent 14 years

(Cl. D81—21)

To all whom it may concern:

Be it known that I, Walter W. Kennedy, a citizen of the United States, residing at Rockford, in the county of Winnebago and State of Illinois, have invented a new, original, and ornamental Design for a Sheet Metal Frame for Grilles and the like, of which the following is a specification, reference being had to the accompanying drawing, forming a part thereof.

In the drawing:

Fig. 1 is an elevational view of a sheet metal frame for grills and the like embodying my new design.

Fig. 2 is a fragmentary perspective view of one corner of the frame.

Fig. 3 is another fragmentary perspective view of the frame corner.

I claim:

The ornamental design for a sheet metal frame for grilles and the like, substantially as shown.

WALTER W. KENNEDY.
